UNITED STATES PATENT OFFICE

EDWIN L. RAMSEY AND JOHN SULLIVAN, OF CHICAGO, ILLINOIS

INGOT MOLD

Application filed April 26, 1926. Serial No. 104,517.

The present invention relates broadly to the art of metal molding and more particularly to improved molds adapted to be used in the production of ingots.

5 Heretofore in the art to which the present invention relates considerable difficulty has been experienced in the casting of ingots due to the cavities or pipes formed therein and not infrequently extending throughout the major portion of the length of the ingots. In order to decrease the tendency of the metal to solidify under such conditions that a pipe or cavity is formed in the resulting ingot, efforts have been made to expedite 10 cooling of the lower portion of the ingot and retard cooling of the upper portions. Many different forms of molds have been utilized more or less successfully in this connection, but in the majority of cases recourse has been 15 had to the use of hot tops or feeders of suitable nature tending to cut down heat dissipation and rate of metal solidification in the upper portion of the mold.

In some cases it has been attempted to obtain 20 the results desired by forming pockets or cavities in the side walls adjacent the upper end of the mold, and then filling such pockets with suitable non-conducting material such as calcined lime. While some advantages may flow from such a structure, they are not sufficient to solve the problem.

It has also been proposed to construct the upper portion of an ingot mold of relatively thin metal and substantially enclose such end 25 by a refractory cover or funnel. The thin upper end being unprotected and not supported against distortion, has caused considerable difficulty. Attempts have been made to overcome such difficulties by providing the upper end of the mold with an annular recess. While this construction has had the advantages of uniform insulation, not possible with the individual pockets, and of partial protection to the thin inner wall, the structure has 40 not been so desirable as to produce any very extended use thereof.

The present invention has for certain of its objects the obviating of the objections enumerated, by a combination of the various features under such conditions as to cut down

heat radiation from the upper portion of the mold, protect and support the upper portion against distortion, and insure uniform and complete insulation of the upper portion. In endeavoring to obtain the results possible by 55 the use of a mold as hereinafter more fully described, we found that by using molds having approximately fifty per cent. insulation for a distance of fourteen inches, for example, the pipe or cavity extended nineteen 60 inches within the ingot. By increasing the length of the insulated portion to sixteen inches and insuring seventy-five per cent. insulation, the pipe or cavity was reduced to fourteen inches, while by merely adding 65 twenty-five per cent. more insulation the depth of the cavity was decreased five inches, or nearly thirty-six per cent. It is one of the objects of the present invention, therefore, to obtain insulation which is both as complete and as uniform for the upper end of the mold as possible.

We have also found that it is desirable to support the upper end of the ingot mold to 70 prevent distortion thereof, due to the heat of the metal being cast therein. This is not possible by the use of a neck of reduced thickness, or by the use alone of an annular recess. This invention, therefore, contemplates 75 a structure in which the length of life compares favorably with standard molds and in which the results are much improved.

In the accompanying drawings, there are shown for purposes of illustration only certain preferred embodiments of the present invention, it being understood that the drawings do not define the limits of our invention, as changes in the construction and operation disclosed therein may be made without departing either from the spirit of the present 80 invention or the scope of our broader claims.

In the drawings:

Figure 1 shows one manner of effectively protecting and supporting the upper portion 85 of an ingot mold.

Figure 2 is a view similar to Figure 1, but showing a slightly modified embodiment of the invention,

Figure 3 is a view similar to Figures 1 and 100

2, but showing still another embodiment of the invention,

Figure 4 is a side elevational view, partly broken away and partly in section, and illustrating another embodiment of the invention,

5 Figure 5 is a view similar to Figure 4 but illustrating the invention applied to a mold of slightly different characteristics, and

10 Figure 6 is a top plan view of a mold as shown in either Figures 4 or 5.

15 In carrying out the present invention there may be provided a mold of any desired configuration and constructed in accordance with known methods to provide either a mold of the big-end-up or of the big-end-down type.

20 The contour of the mold cavity, and the character of the mold walls, may be varied as desired and as well understood in the art at the present time.

25 In Figure 4 of the drawings, there is illustrated an ingot mold 2, of the big-end-down type, having a mold cavity 3 of any desired contour. The upper portion 4 of the mold is preferably formed with an annular recess or opening 5 extending continuously around the cavity so as to provide uniform conditions within the zone of the upper portion of the cavity embraced by the recess. In order to accommodate such recess, the wall of the ingot mold adjacent the upper portion may be 30 of slightly increased thickness as clearly indicated in the drawings.

35 The recess 5 provides an inner shell 6 which is relatively thin, and which, due to its light mass, does not tend to quickly chill the molten metal in the mold. In contact with the metal it becomes heated to a comparatively high temperature, as contrasted to a thick wall such as used for the remainder of the mold, and thereby assists in maintaining the 40 body of metal in the upper portion of the mold in molten condition whereby it is available to feed the shinkage of the metal in the lower portion and thus prevent the formation 45 of a pipe or cavity. The provision of the recess also serves to materially reduce the radiation from the upper portion of the ingot, and thereby further assists in maintaining the temperature conditions desired.

50 We are aware that it has heretofore been proposed to construct ingot molds in which the upper portion of the mold has a relatively thin wall, but so far as we are aware, no effective means has heretofore been provided 55 for preventing distortion of such relatively thin portion. In accordance with the present invention a continuously extending recess with a thin inner wall is made entirely feasible by providing a thin connecting rib 7 above the recess and connecting the inner and outer walls to maintain the same in predetermined spaced relation. As indicated in Fig. 3 of the drawings, this connecting rib 60 65 may be provided with openings 8 predeter-

minately located and serving as core openings during the manufacture of the ingot.

The continuously extending annular recess not only provides for uniform insulation throughout the periphery of the upper portion of the ingot, whereby desirable results are obtained as hereinbefore set forth, but it makes possible, by reason of the outer wall and the connecting ribs, the use of a thin body of metal adapted to become highly heated during the formation of an ingot.

70 In casting ingot molds of the type here described, a mold core fills the continuously extending recess. By allowing that core to remain in the finished ingot mold an insulating band surrounds the thin inner wall at the top of the ingot mold, reducing the radiation of heat from said wall when ingots are poured, and affording additional re-enforcement for the wall. Desirable replacement of that 75 insulating band by another of refractory material packed in the recess is accomplished 80 through the core openings 8.

85 In Figure 5 of the drawings there is indicated a mold structure similar to that shown in Figure 4, but in which the mold cavity is of different shape, in accordance with known practices. In this figure, parts corresponding to parts already described are designated by the same reference characters as those heretofore used but having a prime 90 affixed thereto, the drawing being more particularly for the purpose of illustrating the adaptability of the invention to molds of different constructions.

95 In Figure 6 of the drawings there is illustrated a mold having a continuously extending recess providing a thin inner wall 16, this wall in the present case not being connected to the outer wall structure. A reinforcement 100 is provided, however, by means of the refractory hot top 17 which is bodily slipped into position so as to provide feeding means for the mold, reinforcing means for the inner wall and insulating means reducing to a minimum the radiation of heat from the molten metal within the zone confined by the annular recess.

105 In some cases in order to prevent the upper portion of the inner shell or wall 16 from erosion under the action of the hot metal it is desirable to provide protecting means co-operating therewith. In Figure 2 of the drawings there is illustrated a hot top 17' having a depending portion 18 adapted to extend 110 within the mold a predetermined distance and protect the inner wall against the action of the molten metal.

115 In still other cases it has been found desirable to provide for the complete protection of the inner wall 16, and in such cases the hot top may be formed with an inner portion 18' of a length such as to completely shield the inner thin wall portion.

120 It will be understood that the hot tops uti- 125

lized in accordance with Figures 1, 2 and 3 of the drawings may be of known construction and composition, the utility of the invention not being limited to a hot top of any particular characteristics. We have found, however, that very desirable results are obtained by the use of one-piece hot tops which may be bodily slipped into position and which are sufficiently compact to provide the reinforcement desired to prevent distortion.

10 Certain advantages of the present invention arise from the provision of an ingot mold having the upper portion uniformly insulated to minimize the heat radiation, and in which the construction is such as to provide a thin inner wall effectively maintained against distortion.

20 Other objects of the present invention arise from the provision of an ingot mold in combination with a bodily removable hot top which co-operates with a continuously extending recess, and in which the mold is constructed to protect that portion of the hot top which projects into the recess.

25 Still other advantages of the invention arise from the provision of an ingot mold having an upper portion of relatively thin metal with means for protecting such portion from the action of the molten metal.

30 We claim:

1. In combination, an ingot mold having a recess formed in the wall adjacent one end of the mold and providing a relatively thin inner wall, and a bodily removable hot top 35 entering said recess and engaging opposite sides of said relatively thin inner wall for reinforcing the same.

2. In combination, an ingot mold having a continuously extending recess adjacent one 40 end providing an outer wall and a relatively thin inner wall, a hot top extending into said recess between said walls and over the upper edge of said inner wall and thence downwardly into the cavity in the mold.

45 3. The combination with an ingot mold having a recess in the upper end thereof, of protecting means comprising interconnected portions embracing and extending on opposite sides of one of the walls of said recess.

50 4. The combination with an ingot mold having a continuously extending recess adjacent one end thereof providing a relatively thin inner wall, of refractory means entering said recess and having a connected projection extending over the upper edge of the inner wall and downwardly into the mold 55 for cooperating with the inner side of said relatively thin wall.

5. In combination, an ingot mold having 60 an upper end portion, and a bifurcated hot top straddling said portion.

6. In combination, an ingot mold having a relatively thin upper end portion, and a bifurcated hot top straddling said portion.

65 7. In combination, an ingot mold having a

bifurcated upper portion, and a bifurcated hot top cooperating therewith with one portion of the hot top between the portions of the mold and one portion of the mold between the portions of the hot top.

8. In combination, an ingot mold having a bifurcated upper portion, and a bifurcated hot top cooperating therewith with one portion of the hot top between the portions of the mold and one portion of the mold between the portions of the hot top and bodily removable therefrom.

In testimony whereof we affix our signatures.

EDWIN L. RAMSEY. 80
JOHN SULLIVAN.
